ATTORNEY

UNITED STATES PATENT OFFICE

FRANK PRAVDA, OF DUNELLEN, NEW JERSEY

CARRIER FOR PNEUMATIC TUBES AND THE LIKE

Application filed July 24, 1930. Serial No. 470,269.

This invention relates to containers and specifically to carriers for pneumatic tube systems.

The main object of my invention is to provide a container or a carrier which may be easily and quickly opened, and closed the same way.

Still another object of this invention is to provide a device of the character mentioned which will act semi-automatically.

Other objects of the invention will be apparent as the specification of the same proceeds, and among them are: to provide a device as characterized which will be simple and compact in construction, inexpensive to manufacture and efficient in use.

It is a well known fact that the carriers of pneumatic tube systems used for mails, in department stores, banks, and other establishments, are rather awkward and inefficient in construction, and particularly it requires a comparatively tedious and long operation to open them and extract their contents, or to close them after they have been filled.

My invention aims to provide a carrier which normally is closed, but the lid of which may be opened and turned out of the way by a very easy operation, and it mainly consists of a tubular relatively stationary container and a second tubular container slideable in the first one, a rotatable post is secured in the bottom of the relatively stationary lower portion of the carrier, while the slideable upper portion of said carrier is upwardly urged by a helical spring placed thereunder in the stationary portion of the device. The post carries the lid for said slideable upper portion and in the normal position thereof it exactly and tightly closes the upper open end of said slideable tube. The upper portion of said post, near said lid secured thereon, is flat and a guide device is secured to the inside of the slideable portion having a slot therein through which said flat portion can travel. Said flat portion is twisted at a certain portion thereof forming something like a screw thread therein, so that upon the movement of said flat portion of the post through said slot, the post, and the lid carried thereby, will be caused to turn inwardly or outwardly,

respectively. These motions of the lid may be timed to coincide with the normal and with the downwardly pressed positions of the slideable tube, so that said lid will clear the carrier, when it is desired to open the same, and automatically close it after it has been emptied and newly charged.

In the drawing forming part of this specification and in which similar characters of reference relate to similar parts:

Fig. 1 is a perspective view of my device in an open position, while

Fig. 2 is a central sectional view showing the same in a closed position.

Referring now, more closely, to the drawing by characters of reference, the numeral 10 indicates the lower relatively stationary portion of my device, consisting of a tube 11, and an integral, or if desired, a separate bottom 12 for the same. The upper relatively movable or slideable portion of the device consists of a longer inner tube 13 set into the upper end of the tube 11, and a shorter outside tube 14 is secured on the upper portion of said long inner tube 13 by riveting or by any other appropriate means (not shown). A strong helical spring 15 is placed between the tube 13 and the bottom 12, normally urging said tube in an upward direction. The stationary tube 11 has a plurality of guide slots 16 provided in its circumference and guide pieces 17 are secured to the lower end of the tube 13, said pieces being slideable in the slots 16, not only to guide said tube in its motion, but also to prevent its turning and to provide upper and lower limits for its sliding motion.

A post 18 is loosely and rotatably secured in the bottom 12, as for example by means of the rivet head 19 and the collar 20, at its lower end and on the two sides of the bottom 12.

The upper portion 21 of the post 18 is flat and a guide piece 22 is secured on the inner side of the tube 13 by the rivets 23 thereon, or by any appropriate means, and said guide piece is provided with a slot 24 through which the flat portion 21 of the post may easily slide. A part 25 of said flat portion is twisted forming a structure similar to a hel-

ical screw, and the upper end of said post carries a cover or lid 26.

Normally the tube 13 is pushed into its uppermost position by the spring 15, and 5 the post 18, flat portion 21, and lid 26, occupies the position shown in Fig 2, thereby closing the opening of the tube 13.

When it is desired to open the carrier, the tube 13 is pushed downwardly as indicated 10 by the arrow 27, which causes the twisted portion 25 of the post 18 to pass through the slot 24 and this motion will cause the post 18 to make a half turn so that the lid 26 will be turned outwardly freeing the upper opening 15 of the tube 18, as shown in Fig. 1. In such a situation the contents of the tube may be easily removed or the same charged and upon releasing the downward pressure on the tube 13 the same will be moved in an 20 opposite direction to that shown by the arrow 27, under the influence of the spring 15 and the twisted portion 25 will pass through the slot 24 in a reverse direction, whereby said post will describe a half turn in the 25 reverse direction and the lid 26 will move inwardly into its closed position, shown in Fig. 2.

Felt cushion disk 28 may be secured to the 30 bottom of the device, having a larger diameter than the lower tube so as to insure a comparatively air tight closure between the tube and the carrier, while at the same time it causes the various tubes described to move through the tube of the pneumatic tube system 35 without touching the same and without undue friction.

My device may be made of tubular fibre, metal or any other appropriate material.

It is understood that changes and variations 40 may be made in the parts and combinations of my invention and I hereby reserve all my rights to any and all such changes as may be within the spirit of the invention and the scope of the appended claims.

45 I also want to remark that upon the pushing downwardly of the tube 13 the contents of the carrier, like papers, etc., will be automatically partially exposed, projecting upwardly, which again greatly aids in emptying or charging the carrier. My carrier 50 also may be made substantially shorter than the carriers used at present for the same service and of the same capacity.

What I claim as new, is:

55 1. In a container, a lower relatively stationary portion, and an upper portion slid- 60 able in relation thereto; a lid for said upper portion, and means to open said lid when said upper portion is pushed in a downward direction.

65 2. In a container, a lower relatively stationary portion and an upper portion slid- 65 able in relation thereto; a lid for said upper portion, means to open said lid when said upper portion is pushed in a downward direc-

tion, and means to normally keep said upper portion in an upwardly pressed position and said lid closed thereon.

3. In a container, a lower relatively stationary portion and an upper portion slid- 70 able in relation thereto; a lid for said upper portion, means to open said lid when said upper portion is pushed in a downward direction, and means to normally keep said upper portion in an upwardly pressed position 75 and said lid closed thereon, said means to open said lid upon the movement of the upper portion including a member secured to the said lower relatively stationary portion of the container, said member carrying the lid so that upon a downward sliding of the upper portion, the upper end thereof will be exposed and the lid lifted therefrom.

4. In a container, a lower relatively stationary portion and an upper portion slid- 80 able in relation thereto; a lid for said upper portion, means to open said lid when said upper portion is pushed in a downward direction, and means to normally keep said upper portion in an upwardly pressed position 85 and said lid closed thereon, said means to open said lid upon the movement of the upper portion including a member secured to the said lower relatively stationary portion of the container, said member carrying the lid so that upon a downward sliding of the upper portion, the upper end thereof will be exposed and the lid lifted therefrom, said member carrying the lid being rotatable and means being interposed between said slid- 90 able upper portion and said member whereby the same is turned when said upper portion is downwardly pressed so that said lid will be lifted from said opening and also turned in an outward direction.

5. A container, comprising a tubular relatively stationary lower portion and a tubular upper portion slid- 100 able in relation to said lower portion; a rotatable post secured in the bottom of said lower portion; resilient means interposed between the bottom of said lower portion and the lower end of said slid- 105 able upper portion normally urging said upper portion in an upward direction; a lid secured to the upper end of said post normally closing the upper open end of said slid- 110 able portion; a flat upper portion for said post and a guide secured to said slid- 115 able upper portion of the container having a slot therein through which said flat portion of the post may travel, said flat portion also having a twist provided therein whereby said post and said lid will be caused to turn in an outward or in an inward direction, respectively, when said upper portion of the container is caused to move in a downward or upward direction in relation to said lower portion.

6. A container, comprising a tubular relatively stationary lower portion and a tubular upper portion slid- 120 able in relation to said

lower portion; a rotatable post secured in the bottom of said lower portion; resilient means interposed between the bottom of said lower portion and the lower end of said slidable upper portion normally urging said upper portion in an upward direction; a lid secured to the upper end of said post normally closing the upper open end of said slidable portion; a flat upper portion for said post and a guide secured to said slidable upper portion of the container having a slot therein through which said flat portion of the post may travel, said flat portion of the post also having a twist provided therein whereby said post and said lid will be caused to turn in an outward or in an inward direction, respectively, when said upper portion of the container is caused to move in a downward or upward direction in relation to said lower portion and guide pieces secured to said slidable portion of the container playing in guide slots provided in said relatively stationary lower part thereof to prevent the relative rotation of said two parts and also to limit the relative movement of the two against one another.

Signed at New York, in the county of New York, and State of New York, this 18th day of July, 1930.
